UNITED STATES PATENT OFFICE.

WALTER F. CLOWES, OF ST. LOUIS, MISSOURI.

DESIGN FOR A BOOK-MARK.

SPECIFICATION forming part of Design No. 22,481, dated May 30, 1893.

Application filed April 3, 1893. Serial No. 468,940. Term of patent 3½ years.

To all whom it may concern:

Be it known that I, WALTER F. CLOWES, of the city of St. Louis, State of Missouri, have invented and produced a new and original 5 Design for Book-Marks, of which the following is a specification, reference being had to the accompanying drawings, showing a part thereof.

Figure 1 is an elevation in perspective of 10 my book-mark showing the character of the design; and Fig. 2 is a cross section taken through the prongs or leaves thereof.

The leading feature of my design consists of three leaves or prongs disposed adjacent 15 to each other; the center one of said prongs is slightly elevated above the plane of the other two so that an end view or sectional view through the prongs presents the appear-

ancee as shown in Fig. 2 of the drawings. The said prongs or leaves are of equal length and 20 at one end terminate with their corners slightly cut so as to round off the sharp points otherwise produced by the angles of the corners. At the other end of the prongs or leaves is superposed a characteristic head or 25 portrait of Columbus.

Having described my invention, what I claim is—

The design for a book-mark substantially 30 as shown and described.

In testimony whereof I affix my signature in presence of two witnesses.

WALTER F. CLOWES.

Witnesses:

T. PERCY CARR,
EMIL STAREK.
